Patented Apr. 11, 1916.

UNITED STATES PATENT OFFICE.

CASSIUS M. GAY, OF LOS ANGELES, CALIFORNIA.

PROCESS AND APPARATUS FOR RECOVERING VOLATILE HYDROCARBONS FROM CRUDE OIL.

1,179,001.

Specification of Letters Patent.

Patented Apr. 11, 1916.

Application filed September 9, 1913. Serial No. 788,818.

To all whom it may concern:

Be it known that I, CASSIUS M. GAY, a citizen of the United States, residing at Los Angeles, in the county of Los Angeles, State 5 of California, have invented certain new and useful Improvements in Processes and Apparatus for Recovering Volatile Hydrocarbons from Crude Oil, of which the following is a description, reference being had 10 to the accompanying drawing, and to the figures of reference marked thereon.

The invention relates to the process and apparatus for recovering volatile hydrocarbons from crude oil, and more especially 15 for recovering gasolene.

It is well known that many of the crude oils contain gasolene or other volatile hydrocarbons. It has been the practice of oil producers to treat the crude oil by passing the 20 same through a "topping" plant, which is simply a heating plant in which the oil is raised to a high temperature and the lighter products driven off are condensed in coolers. The product of this partial distillation is not 25 sold commercially, but is sent to the refinery, where it is further treated and gasolene or other salable volatile hydro-carbons obtained.

An object of the present invention is to 30 provide a process of treating the crude oil as it comes from the well, whereby a salable gasolene or other volatile hydro-carbon is directly obtained.

A further object of the invention is to 35 provide an apparatus whereby the above process may be carried out and wherein the natural gas or other carrier gas utilized in the process may be reclaimed and again used for separating the gasolene or other volatile 40 hydro-carbons from the oil.

These and other objects will in part be obvious, and will in part be hereinafter more fully described.

The figure of the drawings illustrates 45 more or less diagrammatically an apparatus embodying my improvement, and for carrying out the improved process.

In the treating of the oil in order to recover the lighter products by the processes 50 heretofore used, wherein the oil is heated to a high temperature, the distillates are of a low grade.

The present invention consists generally in separating the volatile hydrocarbons from the crude oil by a process which 55 does not require a heating of the oil to a high degree, and, therefore, the distillates recovered are of a much higher grade. This is accomplished by atomizing the crude oil with natural gas which has a great affinity for gasolene and other volatile hydrocarbons. This atomized oil is passed to condensers where it is subject to condensation, and the gasolene or other volatile hydrocarbons held in suspension by the 60 natural gas is thrown down and recovered, and this volatile hydro-carbon is of a high grade and a readily salable quality.

Referring more in detail to the apparatus shown in the accompanying drawing, the 70 process will be better understood from a description thereof. This apparatus consists of a saturater 1, which, as herein shown, is in the form of a cylindrical metal chamber. The crude oil is drawn from the well or 75 from a reservoir in which it is stored by an oil pump 2. The oil is delivered through a pipe 3 to an oil heater 4, where the oil is subjected only to sufficient temperature to aid in the atomizing of the same. From the 80 oil heater the oil is delivered to the atomizers 5 and 6, which project into the saturating chamber 1, at points adjacent the bottom thereof. When natural gas is used for atomizing the oil, said gas is passed from a gas 85 compressor 7, to a gas receiver 8, and from the gas receiver 8 through pipes 9 and 10 to the atomizers. It will be understood that the pipes delivering the oil and the gas to the atomizers are supplied with suitable 90 valves, whereby the proper amount of gas may be regulated and also the pressure of the gas and oil as delivered to the saturater. At the top of the saturater 1, I have provided an outlet pipe 11. Baffle plates 12 95 and 13 are arranged across the upper end of the saturater. The heavier oils, which are not atomized, are held back by the baffle plates and collect at the bottom of the saturater, and pass out through a pipe 14. The 100 saturater is preferably kept at approximately atmospheric pressure, so that the gas will expand as much as possible and attain the highest practical degree of saturation,

In order to avoid the use of a safety valve, or vacuum valve on the saturater, I extend the drain pipe 14 downward to form a very deep siphon. The discharge end 15 of the siphon is some distance below the bottom of the saturation chamber, which insures a discharge of the heavy oils, whenever pressure within the chamber is substantially at atmospheric pressure or above. The oil 5 passing from the siphon discharge is directed to a pipe 17, which leads to the storage receptacles therefor.

The atomized oil, or gas saturated with the volatile hydro-carbons passes through 10 the pipe 11 to a gas compressor 18. This gas compressor is provided with an intermediate cooler 19, which is regulated in temperature so as to precipitate any of the gross or heavier particles which may pass the baffles 15 in the saturation chamber. From this intermediate cooler and gas compressor the saturated gas passes through a pipe 20, to the first condenser 21, and from the first condenser 21 upwardly through a second condenser 22. These condensers are preferably 20 arranged one above the other, and the cooling water will pass first over the second condenser and then over the first condenser, so that the second condenser will be given a 25 slightly lower temperature than the first condenser. The first condenser is provided with an outlet or collecting pipe 23, through 30 which the low grade volatile hydro-carbon is carried off from the condenser, while the second condenser is provided with a collecting pipe 24, through which the gasolene or 35 other volatile hydro-carbon separated from the gas is drawn. The gas and volatile hydro-carbon not condensed in these two 40 condensers is then passed through a pipe 25, to a third condenser 26. This third condenser is cooled preferably to a temperature of about zero Fahrenheit, and the gasolene or other volatile hydro-carbon separated 45 from the carrier gas is led through a pipe 27 to a suitable storage receptacle.

I have shown herein a pipe 23, connected to the pipe 24, and the pipe 27, and, therefore, the different grades of gasolene 50 or other volatile hydro-carbon separated from the atomized oil may be blended and conveyed to the shipping tanks.

That portion of gas used for atomizing the oil which still resists condensation under 55 the combined pressure and low temperature obtained in the condenser 26, is passed to a receiver 28. The condenser 26 may be cooled by a suitable ice machine 29. Suitable pipes 30 and 31 carry the refrigerating fluid from 60 the ice machine to the condenser 26. The ice machine 29, the oil pump 2, and the gas compressor may all be driven from a suitable gas engine 32. The gas utilized in connection with the engine may be drawn from 65 the dry gas receiver 28.

The gas for atomizing the oil may be taken directly from the well when natural gas is used, or may be taken from the receiver 28 by a pipe 33, which connects therewith.

From the above it will be apparent that I have provided an apparatus wherein the crude oil may be heated sufficiently to assist in the atomizing of the same, after which the crude oil is atomized by a suitable gas, preferably natural gas, the "topped" oil collected and delivered to a storage tank, while the atomized oil carrying the lighter volatile hydro-carbons passes through condensers, and the gasolene or other volatile hydro-carbons are separated from the gas, and the dry gas may be again utilized for atomizing the oil. I have, therefore, provided an apparatus in which the gas used for separating gasolene or other volatile hydro-carbons from the crude oil may be used over and over again, and, in effect, becomes the active medium for separating the gasolene from the crude oil, and carrying the same to a point where the gasolene 70 may be condensed and recovered.

While my invention is especially intended and adapted for the recovering of gasolene, it is also obvious that it may be utilized for recovering other lighter volatile hydro-carbons, as has already been referred to in the 80 description of the process.

While I have also described an apparatus for carrying out my process, it will be obvious that other devices may be utilized for 90 this purpose.

Having thus described my invention, what I claim is:

1. The process of reclaiming gasolene 100 from crude oil, consisting in heating the oil only sufficiently to assist in atomizing the same, and atomizing said oil with natural gas, and subsequently separating the gasolene from the atomized oil by condensation.

2. The process of reclaiming gasolene 110 from crude oil, consisting in heating the oil only sufficiently to assist in atomizing the same, but not sufficiently to drive off distillates, and atomizing the oil with natural gas substantially at atmospheric pressure and 115 finally separating the gasolene from the atomized oil by condensation.

3. An apparatus for treating crude oil, consisting of a saturating chamber, an oil heater, means whereby gas may be utilized 120 for drawing the oil from the oil heater, and for atomizing the oil as it is delivered to the saturater, whereby said gas becomes saturated with the lighter volatile hydro-carbons contained in said oil, and condensers connected with said saturating chamber for separating the volatile hydro-carbons from the atomized oil.

4. An apparatus for treating crude oil, consisting of a saturating chamber, an oil 125

heater, means whereby gas may be utilized for drawing the oil from the oil heater, and for atomizing the oil as it is delivered to the saturator, whereby said gas becomes saturated with the lighter volatile hydro-carbons contained in said oil, and condensers connected with said saturating chamber for separating the volatile hydro-carbons from the atomized oil, and means whereby the gas

may be reclaimed and again utilized for 10 atomizing the oil.

In testimony whereof, I affix my signature, in the presence of two witnesses,

CASSIUS M. GAY.
